ARCH SUPPORT

Jack Gerber, Chicago, Ill.

Application January 22, 1944, Serial No. 519,279

8 Claims. (Cl. 36—71)

This invention relates to an arch support for the human foot and, more particularly, to a flexible arch support capable of conforming to the shape of the shoe and of enabling the foot to conform to the support without the usual discomfort resulting from the "breaking in" process.

As is well-known, the human foot is so constructed that most of the weight of the person is carried by the heel bone. The arch support of my invention is so constructed as to resiliently support this weight, and is so designed that when the weight of the person is on the heel portion of the support the pressure on that portion of the support is transmitted to the forward part thereof and, in time, gradually and continuously causes the longitudinal arch of the support to raise to the right height for the wearer with consequent elimination of the "breaking in" pain.

The foregoing feature of my arch support is made possible by a novel, flexible, hinge-like connection between the metatarsal and longitudinal arch supports of the arch supporter which allows the arch to immediately adjust itself to the shoe and to the individual arch lines of the shoe shank. This hinge-like connection makes the supporter self-adjustable, eliminating all strain on the shoe, adding to the comfort of the wearer and allowing it to be worn comfortably at all times in various shapes and styles of shoe. By virtue of the elimination of strain on the shoe by the arch support and the self-adjustment feature, the shoe wears better; like the shoe on a normal, healthy foot.

The arch support of my invention is simple in design and construction and has other advantages which will be made apparent from the following detailed description of the preferred embodiment of the invention illustrated in the accompanying drawing, in which:

Figure 1 is a top plan view of the arch support for a right foot;

Fig. 2 is a longitudinal transverse section thereof taken along the line 2—2 of Fig. 1;

Fig. 3 is a partially exploded view, in longitudinal section, showing the relationship of the parts making up the arch support;

Fig. 4 is a bottom plan view of the arch support, with the bottom layer thereof broken away to further show the relationship of the parts; and

Fig. 5 is a transverse section thereof taken along the line 5—5 of Fig. 1.

Referring to drawing, the arch support there

illustrated is for the right foot, except for shape, is of the same construction as the arch support for the left foot. The arch support may be made up of five parts: a top layer 10, a bottom layer 12, a metatarsal supporting pad 14, a longitudinal main arch support piece 16 and an intermediate cushioning layer 18. The bottom layer may be eliminated, if desired, although this is not preferred.

Top layer 10 is a piece of smooth, pliable leather having its margins shaped to outline a heel portion 20, a front portion 22 and an outwardly curved portion between the heel and front portions, forming when in position in the shoe an upturned wing-like portion 24 which is designed to fit the inner side of the arch. Bottom layer 12 is similarly shaped and is also flexible and is, preferably, made of crepe rubber stock to provide a slip-proof bottom. It may, however, be made from any other flexible material, such as the leather of the top layer, with or without a coating of rubber or other slip-proof material on the bottom thereof.

Metatarsal supporting pad 14 is made of sponge rubber or other resilient material and is conventionally shaped, being thick in the center portion and tapered toward the margins. The main arch support piece 16 is made of suitable material such as leather, thin and wafer-like in form, but thick enough to be somewhat stiff, yet flexible. This piece is shaped to provide a support for the longitudinal arch of the foot and the peripheral margin thereof is skived thin to eliminate unnecessary and undesirable protuberances in the arch support. Cushioning layer 18 is made of suitable material such as sponge rubber and is shaped to provide a heel portion 26 and a front portion 28, bifurcated as at 30 to provide legs 32, 34 which are adapted to straddle the metatarsal pad to a limited extent, as shown. The over-all dimensions of layer 18 are smaller than those of the top and bottom layers so that in the final assembly of the parts the marginal portions of the top and bottom layers 10 and 12 extend beyond the cushioning layer to provide flexible, lateral edges for the arch support, thereby enabling the support to conform readily with the shoe. The legs 32 and 34 and a portion of cushioning layer 18 beyond the bifurcation are skived to eliminate ridges at this portion of the arch support.

The parts may be assembled and secured to each other to form an integral structure by means of rubber or other cement, as follows:

The metatarsal supporting pad is first ce-

mented to the underside of the top layer 10 at the metatarsal region thereof and the cushioning layer 18 is next cemented to the same side of this layer. In cementing layer 18 to layer 10 care should be exercised to position the former so that the fork of the bifurcation and the inner edges of legs 32 and 34 are contiguous with the margin of the metatarsal button, and the rest of layer 18 centered with respect to the margins of layer 10 so that the margins of the latter overlap the margins of the former. Main arch piece 16, except for the forward end 36 thereof, is now cemented to layer 18 somewhat along the inner side of this layer and in the region which is below the longitudinal arch of the foot, with the forward end overlapping the rear portion 38 of the metatarsal pad. End 36 is then cemented to the metatarsal pad and bottom layer 12 is now cemented to the other elements of the arch support to cover them and to provide with the corresponding overlapping margins of layer 10 a flexible lateral edge which extends around the arch support. This flexible edge takes the shape of an upturned wing 40 (Figs. 1 and 5) at the region of the longitudinal arch to conform to the shoe shank and to the inner edge of the longitudinal foot arch when the foot presses against the shoe counter. The remainder of the flexible edge, designated as 42, extends the rest of the way around the arch support and because of the flexibility of this edge the arch support conforms readily to any style of shoe.

It is manifest from the foregoing that at the juncture 44 of the fork of the bifurcation of layer 18 and the edge of the metatarsal pad there is provided a hinge-like joint which enables the arch support to readily fit the shoe and allows the longitudinal arch of the support to raise when the weight of the wearer is on the support. The end 36 of the main arch support piece 16 bridges the trough formed by the contiguous skived edges of the cushioning layer 18 and the metatarsal pad, thereby levelling out this depression and at the same time strengthening the hinge-like joint.

The rubber cushioning layer 18 functions as a shock absorber and provides support and balance to the cuboid region of the foot. The combination of this layer with the main arch support piece 16 and the metatarsal pad, in the manner described, gives the human foot arch not only a brace-like support, but a more natural, flexible support and strengthener which enables the wearer to wear the supports without suffering the usual discomfort of the "breaking in" period.

While I have described my invention in connection with the drawing illustrating a preferred embodiment, it is to be understood that it is not to be construed as limited to this embodiment or to the details thereof since many changes in these details and in the nature of the materials used in making my arch support may be varied without departing from the scope of the invention defined in the appended claims. Thus, for example, the cushioning layer and the metatarsal pad may be formed as a single unitary structure. Neither is my invention to be limited to the method of making the arch support as described herein since changes in this method may be readily made as will be evident to a skilled worker in the art.

I claim:

1. A flexible arch support comprising a layer of pliable material shaped to conform to the

contour of a foot, a metatarsal pad secured to said layer at the metatarsal region thereof, a cushioning member also secured to said layer, said cushioning member extending rearwardly only from said metatarsal pad towards the extremity of said layer to underlie the heel region and longitudinal arch region of said layer, and forming with the metatarsal pad a hinge-like joint, and a stiff, yet flexible main arch support piece secured to said member beneath the longitudinal main arch region of said layer.

2. A flexible arch support comprising a layer of pliable material shaped to conform to the contour of a foot, a metatarsal pad secured to said layer at the metatarsal region thereof, a cushioning member secured to said layer at the longitudinal main arch, cuboid and heel regions of said layer, a portion of the forward extremity of said member being adjacent to the rear edge of said metatarsal pad to provide therebetween a hinge-like joint, and a stiff, yet flexible main arch support piece bridging said joint and extending rearwardly to underlie the longitudinal main arch region of said layer.

3. A flexible arch support comprising a layer of pliable material shaped to conform to the contour of a foot, a metatarsal pad secured to said layer at the metatarsal region thereof, a cushioning member secured to said layer at the longitudinal main arch, cuboid and heel regions of said layer, a portion of the forward extremity of said member being adjacent to the rear edge of said metatarsal pad to provide therebetween a hinge-like joint, and a stiff, yet flexible main arch support piece bridging said joint and extending rearwardly to underlie the longitudinal main arch region of said layer, the forward extremity of said piece overlapping the rear portion of said metatarsal pad and being secured thereto, and the remainder of said piece being secured to said cushioning member.

4. A flexible arch support comprising a layer of pliable material shaped to conform to the contour of a foot, a metatarsal pad secured to said layer at the metatarsal region thereof, a cushioning member secured to said layer at the longitudinal main arch, cuboid and heel regions of said layer, the forward portion of said member being bifurcated to provide legs which straddle a portion of said metatarsal pad and the fork of said bifurcation being adjacent to the rear edge of said metatarsal pad to provide therebetween a hinge-like joint, and a stiff, yet flexible main arch support piece bridging said joint and extending rearwardly to underlie the longitudinal main arch region of said layer, the forward extremity of said piece overlapping the rear portion of said metatarsal pad and being secured thereto, and the remainder of said piece being secured to said cushioning member.

5. A flexible arch support comprising a layer of pliable material shaped to conform to the contour of a foot, a metatarsal pad secured to said layer at the metatarsal region thereof, a cushioning member secured to said layer at the longitudinal main arch, cuboid and heel regions of said layer, the forward portion of said member being bifurcated to provide legs which straddle a portion of said metatarsal pad and the fork of said bifurcation being adjacent to the rear edge of said metatarsal pad to provide therebetween a hinge-like joint, a stiff, yet flexible main arch support piece bridging said joint and extending rearwardly to underlie the longitudinal main arch region of said layer, the forward ex-

tremity of said piece over-lapping the rear portion of said metatarsal pad and being secured thereto, and the remainder of said piece being secured to said cushioning member, and a layer of pliable material of the same shape and dimensions as the other layer over-lying the foregoing elements and secured thereto.

6. A flexible arch support comprising a layer of pliable material shaped to conform to the contour of a foot, a metatarsal pad secured to said layer at the metatarsal region thereof, a cushioning member secured to said layer at the longitudinal main arch, cuboid and heel regions of said layer, the forward portion of said member being bifurcated to provide legs which straddle a portion of said metatarsal pad and the fork of said bifurcation being adjacent to the rear edge of said metatarsal pad to provide therebetween a hinge-like joint, a stiff, yet flexible main arch support piece bridging said joint and

extending rearwardly to under-lie the longitudinal main arch region of said layer, the forward extremity of said piece over-lapping the rear portion of said metatarsal pad and being secured thereto, and the remainder of said piece being secured to said cushioning member, and a layer of pliable, slip-proof material of the same shape and dimensions as the other layer over-lying the foregoing elements and secured thereto.

5 7. In the flexible arch support set forth in claim 4 wherein the margin of said layer extends beyond the margin of said cushioning member to provide a flexible over-hanging edge.

10 8. In the flexible arch support set forth in claim 5 wherein the margins of said layers extend beyond the margin of said cushioning member to provide a flexible over-hanging edge.
